UNITED STATES PATENT OFFICE.

AUGUSTE SCHEUCHZER, OF RENENS, SWITZERLAND.

MACHINE FOR REMOVING WEEDS FROM RAILWAY ROADBEDS.

1,402,663.

Specification of Letters Patent.

Patented Jan. 3, 1922.

Application filed March 31, 1921. Serial No. 457,457.

(GRANTED UNDER THE PROVISIONS OF THE ACT OF MARCH 3, 1921, 41 STAT. L., 1313.)

To all whom it may concern:

Be it known that I, AUGUSTE SCHEUCHZER, a citizen of the Republic of Switzerland, residing at Renens, Switzerland, have 5 invented a new and useful Improvement in Machines for Removing Weeds from Railway Roadbeds (for which I have filed applications in Switzerland Dec. 11, 1916, Patent No. 75,218, and in Germany Oct. 1, 1918, 10 Patent No. 330,260;) and I do hereby declare the following to be a full, clear, and exact description of the same.

This invention relates to a machine for removing weeds from railway road beds by 15 means of which a knife carried by a truck is drawn over or through the bed in order to extract and remove weeds growing thereon.

If it were only a question of passing over 20 the road bed with a knife, the latter could be carried by a hand controlled lever at convenient height and brought into contact with the bed. But it has been proved that the weeds cannot effectively be removed by 25 carrying the knife in contact with the bed and that it is much better to draw the knife through the ballast or the like so that the weeds will be effectively loosened and removed.

30 The object of the present invention is to provide a machine in which it is possible to provide an automatic definite but adjustable rise and fall of the knives.

In the accompanying drawings which 35 illustrate one method of carrying the invention into effect,

Figs. 1 and 2 represent a longitudinal section of a machine according to the invention with the parts shown respectively 40 in inoperative and operative position,

Fig. 3 is a plan view corresponding to Figs. 1 and 2,

Figs. 4-6 show detail views with the knife adjusted at three different heights,

45 Fig. 7 illustrates the device for limiting the amount of lift of the knives.

According to the invention, the knife 1 is not operated by hand but by means of a power cylinder 2 and for this purpose 50 the knife is connected by members 3, 4, 5 with the cross head 6. The inlet of steam to the cylinder 2 is so regulated from a pilot roller 8 through an intermediate member 7 that between the sleepers the knife is carried

somewhat below the level of the track and 55 is drawn through the ballast or the like, but at the sleepers these pilot rollers 8 are operated by any suitable projecting parts (for example the nuts or bolt heads of rail chairs) so that the slide valve of the cylinder 2 is moved and thus the knife is drawn out of the track and over the sleepers. On the return movement of the roller as it moves over the obstruction the knife is lowered and driven into the track. 60

65 Provision is made by which the knives may be carried so high that they will be well above the sleepers; this is effected by the following lift-controlling mechanism. On the truck carrying the whole mechanism 70 a cylindrical guide 9 is arranged pivoted centrally upon a pin 10. Through this cylindrical guide passes a rod 11 which is connected by a link with the connecting-rod 5 and carries collars 12, 13 on either side of 75 the guide. The collar 12 is adjustable and provides the means for determining the lowered position of the knife and the collar 13 determines the raised position thereof. From a post 15 fixed to the cylindrical guide 80 9 swinging cheeks 17 are so carried by an arm 16 that normally they surround the rod 11 between the guide 9 and the collar 13 so that the latter comes against the cheeks as the knife is raised and thus limit the 85 amount of lift.

By means of foot levers 18, 19 which operate shafts 20, 21 these cheeks can be either brought together or simultaneously separated by the driver by means of rods 90 22, Fig. 7. By this means the rod 11 can be moved one step further as in Fig. 6 on the raising of the knife by the cylinder or further still as shown in dotted lines in Fig. 4, so that the mechanism described provides 95 a means for increasing the lift of the knife. This is necessary for clearing crossings top surfaces of which lie above rail level.

I claim:

1. A machine for removing weeds and the 100 like growing between and alongside the rails of railway tracks including a carriage movable along said tracks, ground treating members supported by said carriage and drawn through the ballast of the track bed, 105 means for moving said ground treating members toward and away from the track bed as the carriage advances along said

tracks, and automatically operating control means for the last mentioned means constructed to cause said means to move the ground treating members toward and away from the track bed to insure the passage of the ground treating members over the ties of the tracks.

2. A machine for removing weeds growing between and alongside of the rails of railway tracks, including a carriage movable along said tracks, ground treating members supported by said carriage and movable with the carriage along the tracks, means for moving said members into and out of engagement with the road bed, and controlling means for the last mentioned means including an element associated with the carriage and engaging said road bed.

3. A machine of the kind defined by claim 2 in which the means for moving the ground treating members into and out of engagement with the road bed includes a power cylinder, and in which the control means includes a valve controlling the admission 25 and exhaust of fluid to and from said cylinder.

4. A machine of the kind defined by claim 2 including stops for regulating the depth to which the ground treating members may penetrate the road bed and to limit the distance which said ground treating members may be moved away from said road bed.

5. A machine of the kind defined by claim 2 including means for regulating the dis-

tance which said ground treating members may be moved away from said road bed, said regulating means including a slidable rod, a collar connected to said rod, a relatively fixed abutment through which said rod slides, jaws engageable with said rod adapted to engage said collar for controlling the movement of the sliding rod in one direction, and means for moving said jaws toward and away from said rod.

6. A machine for removing weeds and the like growing between and alongside the rails of railway tracks, including supporting means movable over said tracks, knives carried by said supporting means and adapted to be drawn through the ballast or the like between the ties of the road bed, a power cylinder having a piston, means connecting said piston to said knives to permit said piston to move said knives into and out of the ballast of the road bed, and controlling means for said power cylinder including a pilot roller engageable with the trackway and adapted to control the admission and exhaust of power fluid to and from the cylinder for causing the knives to be forced into the ballast between the ties and to be lifted over the ties.

In testimony whereof, I have signed my name to this specification in the presence 65 of two subscribing witnesses.

AUGUSTE SCHEUCHZER.
